UNITED STATES PATENT OFFICE.

RICHARD C. BRADLEY, OF NEW YORK, N. Y., ASSIGNOR TO EMERY AUTOMATIC CHAIN STORES, INC., OF NEW YORK, N. Y., A CORPORATION OF NEW YORK.

DESIGN FOR A CASING FOR A VENDING MACHINE.

Application filed December 11, 1924. Serial No. 11,666. Term of patent 3½ years.

To all whom it may concern:

Be it known that I, RICHARD C. BRADLEY, a citizen of the United States, residing at New York city, in the county of New York and State of New York, have invented a new, original, and ornamental Design for a Casing for a Vending Machine, of which the following is a specification, reference being had to the accompanying drawing, forming part thereof, in which—

Fig. 1 is a perspective view of the casing for a vending machine showing my new design, and

Fig. 2 is a top plan view thereof.

I claim:

The ornamental design for a casing for a vending machine as shown.

RICHARD C. BRADLEY.
